Inventor:

Karl Georg Ströher.

UNITED STATES PATENT OFFICE

KARL GEORG STRÖHER, OF ROTHENKIRCHEN, GERMANY

HAIR CLAMP FOR PERMANENT HAIR WAVING

Application filed August 27, 1930. Serial No. 478,188.

This invention relates to a hair clamp of the kind used for holding a strand of hair close to the head while it is being heated in a permanent hair waver, and the invention 5 consists in the provision of a pair of hingedly connected arms enclosed in jackets of insulating material which are ribbed on the surface applied to the head so as to promote air circulation whereby the skin will be effectively protected from the heat.

Air circulation is still further promoted by providing the jackets with spacing flanges adapted to form air channels between adjacent clamps.

15 Fig. 1 of the accompanying drawing represents a top view of a clamp according to one construction,

Fig. 2 is a longitudinal section of the same, Fig. 3 is an end view seen from the right 20 of Fig. 1,

Fig. 4 is a cross-section, and

Figs. 5 and 6 are cross-sections of different modifications.

The clamp comprises two arms 1 and 2 25 which are connected at one end by means of a hinge element 3 so that they can be opened out for admitting a hair strand and for clamping the latter between them. At the free ends of the arms a closing member 4 is provided. This closing member is preferably in the form of a fork which is pivoted to one arm and adapted to be turned by means of a finger piece 5 over the end 6 of the other arm, as shown in Figs. 1 and 3, said end being 30 rounded off and recessed as shown at 7.

The arms are enclosed in jackets 8 of insulating material so as to protect the skin from the heat of the hair waver, the clamp being applied to the hair strand close to the 40 head. That face of the jacket which comes nearest the head is preferably ribbed as shown at 10 so as to form channels through which the air can circulate and form a further protection for the skin. The jackets are 45 formed with recesses 11 wherein the closing member 4 is accommodated. At the outer sides of the jackets, spacing flanges 9 are formed which may extend either from the face which comes nearest the head, as shown 50 in Fig. 5, or from the opposite face, as shown

in Figs. 3 and 4. In the latter instance adjacent clamps will form channels between them through which air circulation is further promoted.

In the modification shown in Fig. 6, the 55 jackets are of oval cross-section and will therefore form an additional, enlarged air channel between them and the head.

I claim:—

1. A hair clamp for permanent hair waving, comprising a pair of hingedly connected arms, a pair of insulating jackets enclosing said arms, means connected with said arms for closing the clamp, parts of the exterior surfaces of said jackets being adapted to 60 come in contact with each other when the clamp is closed, and grooves formed on other parts of the exterior surfaces of said jackets to provide for a circulation of air.

2. A hair clamp for permanent hair waving, comprising in combination, a pair of 65 hingedly connected arms, insulating jackets having exterior surfaces provided with grooves, said jackets enclosing said arms, and a flange on each of said jackets, said 70 flange projecting at right angles from the exterior side surface of said jackets and forming a groove with said surface.

3. A hair clamp for permanent hair waving, comprising in combination, a pair of 75 hingedly connected arms, insulating jackets having exterior surfaces provided with grooves, said jackets enclosing said arms, a flange on each of said jackets, said flange 80 projecting at right angles from the exterior side surface of said jackets and forming a groove in combination with said surface, and a forked closing member pivoted to the free end of one arm and adapted to engage over the free end of the other arm, the jackets 85 being recessed for the reception of said closing member.

KARL GEORG STRÖHER.
